UNITED STATES PATENT OFFICE.

WILLIAM J. EVERETT, OF INDIANAPOLIS, INDIANA, ASSIGNOR OF THIRTY PER CENT
TO BUDD L. MORRISON, OF INDIANAPOLIS, INDIANA.

FEED-WATER PURIFIER FOR LOCOMOTIVES.

Application filed April 16, 1920. Serial No. 374,389.

This invention relates to a feed water heater and purifier adapted for use on boilers for causing the removal of impurities contained in the fresh water fed therein, 5 thereby preventing said impurities from being transmitted to the boiler and forming a scale thereon.

The full nature of this invention will be understood from the accompanying drawings and the following description and claims.

Fig. 1 is a cross section through a locomotive boiler looking toward the rear thereof taken just forward of the feed water mounting. Fig. 2 is a side elevation of a portion of a locomotive boiler showing the feed water purifier in position thereon. Fig. 3 is a section taken on the line 3—3 of Fig.

2. Fig. 4 is a section taken on the line 20 4—4 of Fig. 3. Fig. 5 is a section taken on the line 5—5 of Fig. 3.

In the drawings there is shown part of a locomotive having a boiler 10 supported in the usual manner upon a chassis and spring 25 construction, not shown herein, and the driving wheels 11. At the rear of the boiler there is a cab housing 12 having windows or lookouts 13, and a fire box 14 extending below the boiler, the construction of the locomotive being of the common type well known and in use.

In applying the feed water heater and purifier to the boiler it is desirable and necessary to so arrange it with respect to the locomotive that it will not interfere with any of the working parts of the locomotive, be out of the way and especially will be arranged so as not to intercept the view of the operators through the windows or lookouts 35 13.

40 To accomplish this the feed water heater and purifier is constructed as will be hereafter described, and mounted or installed upon the boiler toward the rear thereof by simply cutting a hole 15 in the bottom of said boiler and securing the various parts thereto by riveting.

To form and construct the purifier so as to be adaptable to this type of boiler, a sludge drum 16 is made of boiler plate, circular in cross section, about 18 inches in diameter and 26 inches long, having a dished bottom 17 riveted thereto, and a collar or plate 18 about the top thereof and extending radially from said drum so as to form flanges adapted to be riveted to the bottom

of the boiler. The plate 18 surrounds the top of the drum and there is provided a downwardly projecting neck 19 opening into the drum and adapted to register and communicate with the opening 15 of the boiler. 60 Extending laterally from each side of the drum there are precipitating pipes 20 communicating with said drum through the elbows 21 and collars 22. Deflecting members 23 are mounted on the inside of said drum so as to engage and baffle the water discharged downwardly through the pipes 20 and cause it to hug the sides of the drum so as not to disturb the contents thereof. The pipes 20 extend upwardly at an angle 65 70 hugging the lower surface of the boiler and are connected to the upright pipes 24, which are a continuation thereof, by the elbows 25.

The pipes 20 and 24, and their connections, act as precipitating pipes and mixing 75 chambers wherein the fresh water and the heated water from the boiler are thoroughly mixed and slowly fed into the drum, during which the foreign matters and impurities will become freed and precipitate to the bottom of the drum. At the top of the pipes 24 which with their connections embrace the bottom and sides of the boiler, there are feed water pipes 26 which communicate with the water tank and are controlled by any 80 suitable means, not shown herein. The feed water pipes project into the precipitating pipes and discharge the fresh water through perforated nozzles 27, as shown in Fig. 2. Communicating with each side of the boiler 85 90 there are lead pipes 28 for conducting the hot water from the boiler into the precipitating pipe. In each elbow 25 there is provided a projecting boss having an opening closed by a plug 29 in which a hose or other means 95 may be placed for discharging a strong current of water for cleaning the pipes and drum.

The action of the purifier is as follows: 100 The hot water from the boiler circulates through the purifier as indicated by the arrows, entering the top of each precipitating pipe and passing down into the drum and back through the bottom of the boiler. This is caused by the well known laws of 105 gravity and heat, furthered by the injection into the top of each precipitating pipe adjacent the inlet from the boiler, of cold fresh water thereby decreasing the temperature of the water from the boiler. The cold fresh 110

water is supplied through each nozzle 27 and becomes thoroughly mixed with the hot water, reducing the temperature thereof and causing precipitation therein along with the current induced by the injection of the fresh water. The hot water from the boiler absorbs the cold fresh water, heating it to such a degree that particles of foreign matter are released from the fresh water and tend to precipitate to the bottom of the drum. This precipitation is further effected by the slow passage down the long precipitating pipe, and the disturbance of its stagnation in the drum avoided by the deflecting and baffling of the incoming water by the plates 23. The water standing in the drum before reentering the boiler through the hole 15, however, drops its foreign matter so that when it passes into the boiler it is substantially pure. Any oil or skum arising to the surface of the water is caught in the trap at the top of the drum, adjacent the lower surface of the boiler, and blown off therefrom through the blowoff pipe 30 when said pipe is opened by the operation of the rod 31. The foreign matter accumulating in the bottom of the drum is discharged through the pipe 32 and nozzle 33 when the valve is opened therein by the rod 34, operated by the hand rod 35 through the link 36 which extends upwardly to one side of the boiler in a position to be readily operated and controlled by the engineer.

It will be seen from the foregoing that a constant circulation of the boiler water is obtained, which is most desirable in steam boilers for producing the greatest efficiency embodied in the steam, and this invention, therefore, embodies in one construction a water circulating device in addition to the feeding and purifying features. However, it is not necessary to use two precipitating pipes, as shown herein, as it will be readily understood that any purifier will operate with one, although two are preferable, both for efficiency and uniformity.

The invention claimed is:

1. A feed water purifier for a locomotive boiler, comprising a sludge drum attached

to and opening into the bottom of the boiler, an upright mixing chamber emptying into the sludge drum, a feed water connection opening into the top of the mixing chamber and means for leading water from the boiler into the top of the mixing chamber; the location of said means being beneath the low water level of the boiler, substantially as set forth.

2. A boiler feedwater purifier of the character described in claim 1 in which the means for leading water from the boiler to the mixing chamber is located substantially in a vertical plane that passes through the sludge drum, said plane being at right-angles to the major axis of the boiler, substantially as set forth.

3. A boiler feed water purifier comprising a sludge drum attached to and opening into the bottom of the boiler, an upright mixing chamber emptying into the sludge drum, a baffle plate positioned adjacent the opening through which the fluid from the mixing chamber enters the sludge drum whereby the said fluid is directed against the wall of the said sludge drum and a flange inside said drum extending downwardly from and surrounding the opening into the boiler and a blow-off pipe connected to the upper part of the drum for removal of the floating waste matter, substantially as set forth.

4. A boiler feed water purifier comprising a sludge drum attached to and opening into the bottom of the boiler, an upright mixing chamber emptying into the sludge drum, said mixing chamber discharging into the sludge drum tangentially, a flange inside said drum surrounding the opening into the boiler and extending downwardly from said bottom to a position in the drum relatively free from impurities in the water, and a blow-off pipe connected to the upper part of the drum for removal of the floating waste matter, substantially as set forth.

In witness whereof, I have hereunto affixed my signature.

WILLIAM J. EVERETT.
